Patented Mar. 6, 1917.

UNITED STATES PATENT OFFICE.

FRANK C. WILLIAMS, OF PHILADELPHIA, PENNSYLVANIA, ASSIGNOR TO THE SAFETY BLOCK SIGNAL COMPANY, A CORPORATION OF DELAWARE.

STOPPING MECHANISM FOR RAILWAY-CARS.

1,218,587.

Specification of Letters Patent.

Patented Mar. 6, 1917.

Application filed August 15, 1912. Serial No. 715,179.

To all whom it may concern:
Be it known that I, FRANK C. WILLIAMS, a citizen of the United States, and a resident of Philadelphia, county of Philadelphia, State of Pennsylvania, have invented certain new and useful Improvements in Stopping Mechanisms for Railway-Cars, whereof the following is a specification, reference being had to the accompanying drawings.

This invention particularly relates to mechanism arranged to automatically shut off the motive power and to simultaneously actuate the brake setting mechanism to stop a car or train in accordance with the position of signals disposed at suitable distances along the track.

The principal objects of this invention are to provide stopping mechanism operative to simultaneously control the motive power and brake setting devices of a car or train; to provide means operative to automatically effect the actuation of said stopping mechanism as each signal is passed, and to provide means connected through the signal and operative when said signal is "safety" set to automatically reset said stopping mechanism before it has affected the power controlling or brake setting devices to perform its function of stopping said car or train.

Other objects of this invention are to provide a tripping member forming a normally closed electric circuit, operative when broken in any manner, to effect the actuation of the stopping mechanism; and to provide means connected to effect the actuation of said stopping mechanism when the pressure in the system falls below a predetermined limit.

This invention further includes pneumatically actuated mechanism primarily controlled by a mechanically operated valve actuated by tripping plates disposed at suitable distances along the track, and secondarily controlled by an electrically actuated valve, normally maintained in closed position by a normally closed electric circuit which is arranged to be broken by the actuation of the mechanically operated valve or by the actuation of the pneumatically actuated mechanism.

This invention comprehends a series of signals each having indicating means arranged, when in "safety" position to bridge

separated contact terminals which are respectively connected by electrical conductors to the track rail and to an insulated portion of the plate for tripping the valve controlling the stopping mechanism, the partial circuit thus formed being arranged to complete the partial circuit carried by the car or train for actuating the re-setting mechanism.

This invention also includes all of the various novel features of construction and arrangement hereinafter more definitely specified.

In the accompanying drawings, Figure 1 is a diagrammatic illustration of the stopping mechanism, and the parts connected therewith, showing a convenient embodiment of this invention, and Fig. 2 is a fragmentary elevational view of the tripping mechanism and its position relative to the track rail which is shown in transverse section.

Referring to the drawings, one embodiment of this invention comprises stopping mechanism which is shown in connection with a locomotive, comprising a boiler 5, and a truck wheel 6 arranged to traverse the track 7. Suitably disposed along the track 7 are tripping plates 9, each having an insulated portion 10 connected by the electrical conductor 11, through the battery 12 with the contact terminal 14 of the signal 15, which has the semaphore 16 carrying the knife switch 18 arranged to bridge the terminal 14 and the terminal 19, which latter is connected by the electrical conductor 20 with the track rail 7.

The tripping plates 9 are arranged to be engaged successively by the tripping roller 21 mounted on the shaft 22 journaled in the bearing box 24 which is yieldingly suspended by the hanger bolts 25 and 26 from the bolster 27 which is carried by the locomotive. The bearing box 24 is normally pressed downwardly by the springs 28 and 29 respectively surrounding said hanger bolts 25 and 26 and disposed between the lower surface of the bolster 27 and the upper surface of the bearing box 24. The roller 21 is provided with an insulated electrical conductor ring 30 extending concentrically adjacent to the periphery of said roller, and having its opposite ends extended inwardly, and respectively connected with the brush

rings 33 and 34 for insuring the operation of said roller as hereinafter more fully described.

The engagement of the roller 21 with the inclined surface of the plate 9 effects an upward movement of the bearing box 24 which is operative to open the valve 36 having the valve disk 37 provided with the depending stem 38 terminating slightly above the bearing box 24, but in such relation thereto that when said box is uplifted by the engagement of the roller 21 with the plate 9, the valve disk 37 will be uplifted from its seat 40 in the valve 36 in opposition to the pressure of the spring 41 which normally tends to hold said disk on said seat.

The valve 36 when opened affords connection between the ports 42 and 43, the port 42 being connected by the pipes 45, 46 and 47 with the pressure reservoir 48, and the port 43 being connected by the pipes 50 and 51 with the cylinder 52 of the actuating mechanism.

The cylinder 52 is provided with a piston 54 having the piston rod 55 which also carries the piston 56 of relatively greater surface, in the cylinder 57, which is connected by the pipe 58 with the port 59 of the valve 60, having the port 61 connected by the pipe 62 and pipe 47 with the reservoir 48, said ports 59 and 61 being controlled by the valve disk 63 having the depending stem 65 connected with the conical valve plug 66 arranged to close the passage-way 67 between the port 59 and the exhaust outlet 68, the valve plug 66 being extended through the core 70 of the magnet 71 and carrying the armature 72, whereby the movable members of the valve 60, including the valve disk 63, stem 65 and plug 66 may be actuated when the magnet 71 is energized, as herein-after described.

The piston rod 55 carries the collar 73 arranged to engage the lever 74 which is pivotally connected to the casing of the valve 75 by the link 76, and pivotally connected with the stem 77 carrying the opposed conical valve disks 78 and 79 which are arranged to alternately engage their respective seats when actuated by said collar 73 engaging the lever 74, the valve disk 79 having the spring 80 normally tending to shift it to its closed position, as shown in Fig. 1.

The valve 75 is provided with the ports 82 and 83, the port 82 being connected with the train pipe 84 and the port 83 being connected by the pipe 86 with the cylinder 87 having the piston 88 connected by the piston rod 89 with the bell crank lever 90 which is operative to release the throttle lever 91 as hereinafter described.

The cylinder 87 is provided with the relief port 93 and the exhaust outlet 94 so that when the valve disk 79 is shifted to its open position and communication is established

between the ports 82 and 83, and consequently between the train pipe 84 and the cylinder 87, the piston 88 is shifted in the direction of the arrow indicated in the cylinder 87 to a position beyond the exhaust outlet 94 to release the pressure in the train pipe 84 therethrough.

The throttle lever 91 is connected by the link 96 with the bell crank lever 97 which is connected with the stem 98 of the throttle 99 so that when the locking bar 100 of the throttle lever 91 is released by pressing the hand grip lever 101 toward the handle 102, which is effected by the bell crank lever 90 to disengage its lower free end 103 from the notches 104 of the sector 105, said lever is free to be shifted to control the throttle 99, the automatic release of the locking bar 100 being effected by the bell crank lever 90 when rocked on its pivot by the movement of the piston 88 in the direction of the arrow.

It may be here noted that the train pipe 84 may include the well known brake setting devices and as their structure forms no portion of this invention, they have been omitted from the drawing for simplicity and clearness of illustration.

The coils of the magnet 71 have one terminal connected by the electrical conductor 107 with the truck wheel 6 to form an electrical connection with the track rail 7, and the other terminal connected by the electrical conductor 108 with the depending bolt 26 supporting the bearing box 24, whereby electrical connection is made through the roller 21 to the insulated portion of the contact plate 10 disposed along the rail 7.

In order to electrically affect the actuation of the stopping mechanism, the valve disk 37 has an upwardly extending stem 109 provided with a head 110 forming a switch which bridges the cap between the spring contacts 111 and 112, the spring contact 111 being connected by the electrical conductor 113 with the coils of the magnet 114, and the spring contact 112 being connected by the electrical conductor 115 with the brush 116 which contacts with the ring 33 connected through the conductor 30 with the ring 34, which is engaged by the brush 118 connected by the electrical conductor 120 with the spring contact 121. The spring contact 121 is connected with the spring contact 122, when the pistons 54 and 56 are in their inoperative position as shown in the drawing, by the insulated plate 123, forming a switch on the collar 73, and said spring contact 122 is connected by the electrical conductor 125 through the battery 126 with the coils of the magnet 114.

The magnet 114 is provided with an armature 130 which carries a vertically reciprocating valve plug 131 forming part of a valve 132 provided with ports 133 and 134 and an exhaust outlet 135. The valve 132

plug 131 has oppositely disposed conical ends arranged to engage alternately corresponding conical valve seats 137 and 138 to control the ports 133 and 134 and the exhaust outlet 135. When the valve plug 131 is in engagement with its seat 137, it closes the port 133 and simultaneously connects the ports 134 with the exhaust outlet 135; and when the valve plug 131 is in engagement with the other seat 138, it closes the exhaust outlet 135 and simultaneously establishes communication between the ports 133 and 134. The port 133 is connected by a pipe 140 through a regulating valve 141 and a pipe 45 to the port 42 in the valve 36, so that when the circuit, including the magnet 114 is broken, the valve plug 131 falls and closes the exhaust outlet 135 and establishes communication between the ports 133 and 134 of the valve 132, and thus establishes communication from the compressed air reservoir 48 to the cylinder 52, through the pipe 47, pipe 46, pipe 45, regulating valve 141, pipe 140, port 133, port 134 and pipe 51.

The regulating valve 141 is connected by a pipe 143 with the pipe 50, and is of such a construction that when the pressure in the compressed air reservoir 48 is above a predetermined point, no air is permitted to flow from the reservoir through the pipes 47, 46 and 45 and through the regulating valve 141 into the pipe 143, but when the pressure in the compressed air reservoir 35 falls below such a point, the regulating valve 141 will permit the air from the reservoir to flow through the valve 141 and into the pipe 143. As a construction of regulating valve suitable for performing this function is well known, it is not thought necessary to give a complete illustration and description of the details of construction of this regulating valve 141. The purpose of the regulating valve 141 in this instance 40 is to serve as a means for applying the brakes and stopping the train in case the pressure in the compressed air reservoir 48 falls below a predetermined point, and this regulating valve performs this function by permitting air from the air reservoir 48 to flow into the pipe 143 when, and only when, the pressure in the reservoir 48 falls below a predetermined point. When the air is admitted through the regulating valve 141 45 into the pipe 143, it flows through the pipe 143, pipe 50, pipe 51 and into the cylinder 52 where it acts upon the piston 54 to force the piston in the direction of the arrow and thus causes the application of the brakes 50 and the stoppage of the train as will appear hereinafter. The construction of the regulating valve 141 is such that it permits the air to flow freely at all times from the reservoir 48 through the pipe 46 and the regulating valve 141 into the pipe 140, and

the function of the regulating valve is simply to coöperate with the other parts of the mechanism to stop the train in case the pressure in the reservoir should fall to a predetermined point below which it could not be relied upon to perform its functions. 70

The operation of this improved automatic stopping mechanism is as follows: Referring to Fig. 1 and assuming that the 75 semaphore 16 is in the safety position shown by the inclined dot and dash line in Fig. 1, in which position the terminals 14 and 19 are bridged by the knife switch 18, then, as the locomotive moves from right to left past the semaphore 16, and the corresponding trip plate 9 at the right hand of Fig. 1, the roller 21 will be lifted by the inclined surface at the right hand end of the corresponding tripping plate 9. This upward 80 movement of the roller 21 effects the opening of the valve 36 to establish communication between the reservoir 48 through the pipes 47, 46 and 45, valve 36 and pipes 50 and 51 to the cylinder 52, to admit pressure into said cylinder and thereby drive the pistons 54 and 56 in the direction of the arrow indicated on the piston rod 55. Such movement of the piston causes the collar 73 to travel toward the lever 74 until the roller 21 passes over the insulation in the plate 9 85 to the insulated portion 10, whereupon if the signal is "safety" set, as assumed, a closed electric circuit is established through the insulated portion 10 of the plate 9, roller 21, bearing box 24, hanger bolt 26, electrical conductor 108, coils of the magnet 71, electrical conductor 107, wheel 6, track 7, electrical conductor 20, knife switch 18 and electrical conductor 11, including the 90 battery 12, to effect the opening of the valve disk 63 by which pressure from the reservoir 48 is admitted to the cylinder 57 to return the pistons 54 and 56 to their normal inoperative position as shown in the 95 drawing, before the collar 73 has engaged the lever 74, whereby the stopping mechanism is actuated without performing its function of stopping the train. 100

If, however, upon the engagement of the 115 roller 21 with the plate 9 and its insulated portion 10, the semaphore 16 occupies the "danger" position as shown in the drawing, no closed circuit for re-setting the stopping mechanism can be established through the 120 terminals 14 and 19 and therefore the movement of the pistons 54 and 56 in the direction of the arrow indicated on the piston rod 55 continues until the collar 73 engages the lever 74 and effects the movement of the 125 valve disk 79 to its open position, which establishes communication through the ports 82 and 83 from the train pipe 84 to the pipe 86 and cylinder 87, whereby the piston 88 is shifted by the pressure in the train pipe 130

in the direction of the arrow indicated thereon to effect the closing of the throttle 99; the movement of said piston also affords connection between the pipe 86 and the exhaust pipe 94, whereby the pressure in the train pipe 84 being reduced effects the setting of the brakes in a well known manner.

From the above, it will be apparent that the above construction embodies a number of sub-mechanisms of which the train pipe 84 constitutes a part of the braking mechanism or system proper and the valve 78 with its housing and lever 74, is the valve which opens and closes the train pipe to apply the brakes. The pistons 54 and 56 with their cylinders 52 and 57 respectively, the collar 73 and the valve 131 with its casing 132 and the electromagnet 114 connected thereto and operated thereby, together with the electrical connection or circuit in which said magnet 114 is included, constitutes a controlling and actuating mechanism for the valve 78. The tripping roller 33 and the valve 40 and its housing, constitutes a primary actuating mechanism which sets in motion the valve controlling and actuating mechanism above referred to and it operates every time the roller 33 rides over the ramp rail or tripping plate 9, which is in fact a stationary member adjacent the track for operating the primary actuating mechanism. The magnet controlled valve 63, with its housing 60 and air pipe connections, together with the electric circuit in which the magnet 71 is included, constitutes an opposing mechanism, the function of which is to oppose the operation of the controlling mechanism when the electric circuit therethrough is closed by the train when the signal is "safety set". In the embodiment of this invention illustrated in the drawing, the train stopping mechanism is shown as applied to a steam railroad, 91, being the throttle lever. It is, of course, to be understood that the device is just as applicable to electric roads and that any other power controlling mechanism than a throttle, such, for instance, as an electric controller, may be operated in a similar manner by the compressed air from the train pipe when the track valve 78 is opened.

It is not desired to limit this invention to the precise details of construction and arrangement herein set forth as various modifications may be made therein without departing from the essential features of the invention as defined in the appended claims.

60 Having thus described my invention I claim:

1. In a stop mechanism for a car, the combination with a train pipe, a valve to open said train pipe to actuate a brake mechanism a valve operating mechanism, the

full operation of which actuates said valve, actuating mechanism for starting the operation of said valve operating mechanism at every block, a signal, and opposing mechanism controlled by said signal to stop the 70 operation of said valve operating mechanism before it operates said valve and to reset said valve operating mechanism to its normal original position, when said signal is at "safety set" and permitting said valve 75 controlling mechanism to operate to its full extent and open said valve when said signal is "danger set."

2. In a stopping mechanism for a car or train, the combination of a train pipe, a valve to open said train pipe to apply the brakes, a valve controlling and actuating mechanism, the full operation of which will open said valve, a primary actuating mechanism for actuating said valve controlling mechanism and opposing mechanism to oppose the operation of said controlling mechanism, a track, a stationary member for operating said primary actuating mechanism, a signal, and an electric circuit connected to said track and said stationary member and closed by the train or car when the signal is "safety set", said circuit when closed including said stationary member, said actuating member, said opposing mechanism, said signal and said track, and operative when closed to cause said opposing mechanism to prevent the full operation of said controlling mechanism and to reset said controlling mechanism. 100

3. In stopping mechanism for a car, the combination of a valve to operate the brake mechanism, of controlling means operative to open said valve to apply the brakes, a normally closed electric circuit, actuating means coöoperating with said normally closed circuit operative when broken to effect the actuation of said controlling means, a normally open electric signal circuit, a signal included in said normally open signal circuit, restraining means co-operating with said normally open signal circuit for opposing the operation of said controlling means when said normally open signal circuit is closed, and means arranged to consecutively and automatically open said normally closed circuit and to close said normally open signal circuit when said signal is in safety position. 105 110 115

4. In stopping mechanism for a car, the combination with a valve to apply the brakes, of controlling means operative to open said valve to apply the brakes, a normally closed electric circuit, actuating means coöperative with said normally closed circuit for effecting the actuation of said controlling means, a normally open electric signal circuit, a signal included in said normally open signal circuit, restraining means coöperating with said normally 130

- open signal circuit for opposing the operation of said controlling means, and means arranged to consecutively and automatically open said normally closed circuit and to 5 close said normally open signal circuit when the signal is "safety set", said controlling means being actuated as the result of the opening of said normally closed circuit regardless of the position of said signal and 10 the actuation of said controlling means being opposed as a result of the closing of said normally open signal circuit by the car when said signal is "safety set."
5. In stopping mechanism for a car, the combination with a valve for operating the 15 brake system, of controlling means arranged to actuate said valve, a normally closed electric circuit, a normally open electric signal circuit, a signal included in said normally 20 open signal circuit, means coöperating with said closed circuit for actuating said controlling means, means coöperating with said normally open signal circuit for opposing the actuation of said controlling means, and 25 means controlled by the movement of the car for automatically and consecutively opening said normally closed circuit and closing said normally open circuit when said signal is "safety set".
6. In stopping mechanism for a car, the combination with a track including rails, of a signal, a tripping plate comprising two 30 portions electrically insulated from each other, a normally open electric signal circuit connected to one of said portions and extending to one of said rails through said signal when "safety" set, a valve for operating the brake for said car, controlling means for actuating said valve, a tripping 35 roller carried by said car and arranged to traverse said portions of said plate and coöperating with one of said portions to actuate said controlling means and coöperating with the other of said portions 40 to close an electric circuit through said signal circuit to oppose the actuation of said controlling means when said signal is "safety" set.
7. In stopping mechanism for a car, the combination with a track including rails, of a signal, an elongated stationary tripping plate having a portion of its length electrically insulated from the remaining portion thereof, a normally open electric signal circuit connected to one of said portions and 45 extending to one of said rails through said signal when "safety set", a brake valve for said car, controlling means controlling said valve, tripping means carried by said car 50 and arranged to engage portions of said plate consecutively and when in engagement with the first of said portions of said tripping plate to actuate said controlling means and when in engagement with the second of 55 said portions to close said normally open
- electric signal circuit when said signal is "safety" set to oppose the actuation of said controlling means, said controlling means being operative to open said valve and apply the brakes when said normally open 70 electric signal circuit is not closed when said tripping means is in engagement with the second of said portions.
8. In stopping mechanism for a car, the combination with a track including rails, of a signal, of an elongated stationary tripping plate having a portion of its length electrically insulated from the remaining portion thereof, a normally open electric signal circuit connected to one of said portions and 75 extending to one of said rails through said signal when "safety set", a valve for applying the air brakes to the car, controlling means operative to open said valve, an actuating valve, means coöperating therewith for 80 actuating said controlling means, tripping means carried by said car and arranged to engage said plate to actuate said valve, and means coöperating with said tripping means when in engagement with the insulated portion 85 of said tripping plate to close said normally open electric signal circuit through the engagement of the car with said rail when said signal is "safety set" and opposing means actuated by the current in said 90 normally open signal circuit when said circuit is closed through said signal to oppose actuation of said controlling means.
9. In stopping mechanism for a car, the combination with a track, including rails, of a signal, an elongated stationary tripping plate having a portion of its length electrically insulated from the remaining portion thereof, a normally open electric signal circuit connected to one of said portions of 100 said plate and extending to one of said rails through said signal when "safety set", a brake applying valve for said car, controlling means for actuating said valve, a second valve and means coöperating therewith for actuating said controlling means, tripping means carried by said car and arranged to engage said tripping plate for positively 105 actuating said second valve, and an electric device including connections therefor arranged to coöperate with said tripping means when in engagement with the said insulated portion of said tripping plate to close said normally open signal circuit when 110 said signal is "safety set" and to oppose the actuation of said controlling means.
10. In stopping mechanism for a car or train arranged to traverse a track, the combination with signals disposed at suitable distances, of a fixed tripping plate for each 115 signal, each of said plates having an insulated portion electrically connected to the track rail through said signal when "safety" set, an air brake system, a controlling valve in said system, valve operating means 120 and arranging to engage portions of said plate 125 consecutively and when in engagement with the first of said portions of said tripping plate to actuate said controlling means and when in engagement with the second of said portions to close said normally open

- ranged to control the valve in said system and including tandem arranged cylinders, having pistons of different diameters respectively, means actuated by said pistons to open said valve, a pressure reservoir connected with said cylinders, a valve interposed between said reservoir and the smaller cylinder, means carried by the car and arranged to engage said tripping plates consecutively to open the second mentioned 5 valve for each signal passed, a valve interposed between said reservoir and the larger cylinder, and means electrically connected with the means for engaging said tripping plates, and forming a closed circuit through said insulated portion and through said signal when "safety" set to actuate said last mentioned valve to admit pressure into the larger cylinder and prevent the actuation of the valve in the air brake system.
- 10 11. In stopping mechanism for a car or train arranged to traverse a track, the combination with signals disposed at suitable distances, of a fixed tripping plate for each 15 signal, having an insulated portion electrically connected with the track rail through said signal when "safety" set, an air brake system, a valve in said system, a lever connected to actuate said valve, valve actuating means comprising tandem arranged cylinders 20 respectively having connected pistons of relatively different diameters, means controlled by said pistons to actuate said lever to open said valve, a pressure reservoir, means connecting said reservoir with the respective pistons, a valve interposed in the connection between said reservoir and the smaller cylinder, tripping means operatively connected to open the second mentioned 25 valve by engagement with said tripping plates upon passing each signal to effect the actuation of said pistons and the lever engaging means toward said lever, a valve interposed in the connection between said reservoir and the larger cylinder, and means including a normally open electric circuit which is closed through the tripping means when said signal is "safety" set and when said tripping means is in engagement with the insulated portion of the tripping plate, to 30 actuate said last mentioned valve to cause the arrest of the movement of the pistons and to cause them to return to their inoperative positions before opening the train 35 pipe valve.
12. In stopping mechanism for a car or train arranged to traverse a track, the combination with signals disposed at suitable distances, of a fixed tripping plate for each signal, having an insulated portion electrically connected with the track rail through said signal when "safety" set, an air brake system including a valve operative to effect the setting of the brakes when open, means arranged to open said valve, comprising 40 cylinders respectively having pistons of relatively different diameters, connected together and carrying means to open said valve, a pressure reservoir connected with said cylinders, a valve disposed in the connection between said reservoir and the smaller cylinder, normally tending to open by gravity and closed by means including a normally closed electric circuit, means carried by the car for engaging said plates, said circuit being broken by engagement of said last mentioned means with said plates to admit pressure into said smaller cylinder, a valve interposed between the pressure reservoir and the larger cylinder and normally 45 maintained closed by gravity, electrical means including a normally open circuit which is closed through the signal when "safety" set and when said plate engaging means engages the insulated portion of said plate to operate upon said last mentioned valve to admit pressure into the larger cylinder and to cause the return of said pistons to their inoperative positions.
13. In stopping mechanism for a car or train arranged to traverse a track, the combination with signals disposed at suitable distances, of a fixed tripping plate for each signal, having an insulated portion electrically connected with the track rail through 50 said signal when "safety" set, an air brake system including an air brake valve, means to actuate said valve, comprising cylinders having connected pistons of relatively different diameters, carrying means operative to effect the opening and closing of said valve, a pressure reservoir connected with said cylinders, an electrically actuated valve interposed in the connection between said reservoir and the smaller cylinder and including electrical means comprising a normally closed electric circuit having a switch, means carried in the path of said plates and arranged to be uplifted thereby when engaged therewith to open said switch and effect the actuation of the second mentioned valve by breaking said closed electric circuit, and a valve interposed in the connection between said reservoir and the larger cylinder and having electrical actuating 55 means, included in a normally open electric circuit, including the means for engaging said tripping plates and closed thereby through the "safety" set signal, when engaging the insulated portion of said plates.
14. In stopping mechanism for a car or train arranged to traverse a track, the combination with signals disposed at suitable distances, of a fixed tripping plate for each signal, having an insulated portion electrically connected with the track rail through said signal when "safety" set, an air brake system including an air brake valve for releasing said system, means arranged to actuate said valve comprising cylinders hav- 60

- ing pistons of relatively different diameters, means controlled by said pistons to open said valve, a tripping roller carried in the path of said plates and arranged to be uplifted thereby, an electrical conductor carried by said roller and disposed adjacent to the periphery thereof in insulated relation thereto, and having terminals comprising brush rings surrounding the shaft of said roller, a pressure reservoir connected with said cylinders, a valve interposed in a connection between said reservoir and the smaller cylinder for controlling the same, and means normally holding said last mentioned valve closed and including a normally closed electric circuit having brushes respectively in contact with said terminal rings, and having a switch opened by the upward movement of said roller when engaging said contact plates, and operative to break said closed electric circuit to admit pressure into the smaller cylinder, and a valve interposed in the connection between said reservoir and the larger cylinder, electrically actuated by means including a normally open electric circuit connected through said roller and the insulated portion of said tripping plate when the signal is "safety" set.
15. In stopping mechanism for a car or train arranged to traverse a track, the combination with signals disposed at suitable distances, of a fixed tripping plate for each signal, having an insulated portion electrically connected to the track rails through said signal when "safety" set, throttle controlling mechanism, means automatically actuated to operate said throttle controlling mechanism, comprising a cylinder having an inlet and an outlet, and a piston normally disposed between said inlet and said outlet, an air brake system connected with the inlet of said cylinder and having an air brake valve therein, means arranged to actuate said last mentioned valve comprising cylinders having connected pistons of relatively different diameters, a pressure reservoir connected with each of said cylinders, a valve interposed in the connection between said reservoir and the smaller cylinder, means including a normally closed electric circuit for actuating said last mentioned valve, a valve interposed in the connection between said reservoir and the larger cylinder means, including a normally open electric circuit for actuating said last mentioned valve, and tripping means arranged to engage said plates consecutively to break said normally closed electric circuit for each signal passed, and arranged to close the normally open electric circuit through the corresponding insulated portion of the corresponding one of said plates when the signal is "safety" set.
20. In a stopping mechanism for a car or train, the combination with a signal, a track and a stationary insulated member adjacent the track, of a stop mechanism coöperating therewith and carried by the train or car, and comprising a train pipe, a valve to open said train pipe to apply the brakes, a power controlling mechanism operated from the train pipe when said valve is open, a valve controlling and actuating mechanism, a primary actuating mechanism for operating said valve controlling mechanism and arranged to coöperate with said stationary plate to put said controlling mechanism in operation, and an opposing mechanism to oppose the operation of said controlling mechanism, and an electric circuit, completed by the train when said signal is "safety set," through said stationary member, said actuating mechanism, said opposing mechanism and said track, and operative to cause said opposing mechanism to prevent the operation of said controlling mechanism and to reset said controlling mechanism, said primary actuating mechanism being operative when the said circuit is open or broken to actuate said valve controlling mechanism to its full extent and to open said valve.
25. In stopping mechanism for a car or train arranged to traverse a track, the combination with a signal positioned adjacent said track, of a fixed tripping plate electrically connected to a rail of said track through said signal when "safety" set, an air brake system, a controlling valve in said system, means arranged to control said valve and including a pair of hollow cylinders of different internal diameters provided with pistons of corresponding diameters, means actuated by one of said pistons to open said controlling valve, a pressure reservoir connected to said cylinders, a valve interposed between said reservoir and the smaller one of said cylinders, means carried by the car and arranged to engage said tripping plate to open said last mentioned valve, a valve interposed between said reservoir and the larger one of said cylinders, and electrical means coöperating with said means for engaging said tripping plate for causing the actuation of said last mentioned valve when said signal is safety set to admit pressure into the larger one of said cylinders to prevent the actuation of said controlling valve in said air brake system.
30. In stopping mechanism for a car or train arranged to traverse a track, the combination with a signal positioned adjacent said track, of a fixed tripping plate electrically connected to a rail of said track through said signal when "safety" set, an air brake system, a controlling valve in said system, means arranged to control said valve and including a pair of hollow tandem cylinders of different internal diameters pro-

vided with pistons of corresponding diameters, means actuated by one of said pistons to open said controlling valve, a pressure reservoir connected to said cylinders, a 5 valve interposed between said reservoir and the smaller one of said cylinders, means carried by the car and arranged to engage said tripping plate to open said last mentioned valve, a valve interposed between said reservoir and the larger one of said cylinders, and electrical means coöperating with said 10 means for engaging said tripping plate for

causing the actuation of said last mentioned valve when said signal is safety set to admit pressure into the larger one of said cylinders to prevent the actuation of said controlling valve in said air brake system. 15

In witness whereof, I have hereunto set my hand this 12th day of August, 1912.

FRANK C. WILLIAMS.

Witnesses:

JAY R. GRIER,
CLIFTON C. HALLOWELL.
